UNITED STATES PATENT OFFICE.

PETER G. DAMSTRA, OF HOLLAND, MICHIGAN.

WORK-BENCH.

1,283,401.

Specification of Letters Patent. Patented Oct. 29, 1918.

Application filed March 24, 1917. Serial No. 157,267.

To all whom it may concern:

Be it known that I, PETER G. DAMSTRA, a citizen of the United States, residing at Holland, in the county of Ottawa and State of Michigan, have invented certain new and useful Improvements in Work-Benches, of which the following is a specification.

My invention relates to improvements in work-benches and tables, and its objects are: first, to provide a table or bench that may be readily folded in small space for transferring, storing, shipping, &c.; second, to provide a means whereby the legs of the table or bench may be readily folded to bring them into parallel position, or may be readily removed from the table, or replaced thereon; third, to provide a means whereby the legs may be readily braced or released, when in supporting position on the table.

I attain these objects by the mechanism and arrangement of parts shown in the accompanying drawing, in which Figure 1 is a bottom plan of one end of the bench top with the legs in folded position for storing or shipping. Fig. 2 is an end elevation of a bench showing the bracing elements. Fig. 3 is a bottom plan of one end of the top showing the several slots for securing and operating the leg supporting rail. Fig. 4 is a side elevation of the bench showing the manner of bracing the legs longitudinally of the bench. Fig. 5 is a transverse section of the bench top on the line 5, 5 of Fig. 3, showing the manner of connecting the leg supporting rail by means of the slots in the bench top 1. Fig. 6 is a perspective of the rail holding bracket and bearing; and Fig. 7 is a like view of the locking device on the rail.

Similar reference characters refer to similar parts throughout the several views.

In the construction of this bench I mount the legs 5 upon detached rails, 2. These rails are divided at the longitudinal center into halves, and are connected or assembled in the form of a shiplap, as indicated at 3, in Figs. 1 and 5. The ends of the shiplaps 3 are properly beveled so they may be made to swing into direct alinement when pivotally secured together at 4, and become so firmly locked together as to render the rail practically as firm as an integral rail would be.

When the rail 2, 2 is in place on the bench top 1 the lower end of the pivot pin passes into the slot *e*, and the dovetailed lugs 13, on the rail, pass into the corresponding slots,

c—d, which holds the legs securely in place when folded upon the surface of the bench top. In this position the ends of the legs 5 are engaged and held in place by the springs 9, 9, so the bench may be easily moved from place to place or stored in small space, when desiring to extend the legs, as in Figs. 2 and 4, the rail 2, 2 is swung around into proper alinement, when the dovetailed lugs 13 will be carried around to the open spaces, *c, c*, in the slots *c, d*, and the bearings *h, h* on the rail will be brought into engagement with the corresponding bearings on the brackets 10, and the wings 12 will be made to pass over, and engage the lugs 11 on the brackets and draw the ends of the rails into firm engagement with the brackets.

To remove the legs from the bench top 1 it is only necessary to slide the rails 2, 2 from under the brackets 10, 10 before the legs are folded against the bench top 1, as with the rails in this position the lugs 13, 13 are entirely disengaged from the slots *d, d* and the rails may be readily removed.

As it is necessary to provide proper brac- 80 ings for the legs, when extended to support the bench, I have provided for bracing them laterally by means of braces 7, 7 which are pivotally connected with the rails at the pivot point 4, and securely connected with the legs at the other end, as indicated at *b, b*, in Figs. 1 and 2. For this, as well as for endwise bracing, any available form of brace may be used, the forms herein shown being simply suggestive of the general manner of 90 bracing.

For endwise bracing I have provided a form of brace, shown at 15, in Figs. 1, 2 and 4. This brace is designed to be pivotally secured to the legs, as indicated at *a, a* in the 95 several figures, so they may be readily swung from the position shown in Fig. 1 to the position shown in Figs. 2 and 4, and the free end of the brace is so formed and arranged that it may be made to rest upon the surface 100 of the bench top, perfectly parallel therewith, and I have arranged brackets, 8, 8 to be secured to the bench top in such a manner that when the braces are extended to supporting position they will pass under the 105 ends of said brackets and will be held firmly in position so the legs cannot be swung either toward, or from the braces.

The brackets 8, 8 should be made of spring metal and clamped upon the wing of the 110

brace sufficiently firmly to avert all danger of the brace swinging out of position. It will be readily understood that this element in my invention may be varied to meet the requirements of any form of brace I may desire to use, hence I do not desire to restrict myself to any special form of securing device for the free ends of the braces.

The wings 12 are firmly secured to the side of the rail 2, and the brackets 10 are secured to the bench top 1 near the opening *c* of the slot *b-c*, so that when the rail 2 is in the position shown in Fig. 2 and the legs are turned downward into supporting position, the wings 12 will pass over the wings 11 on the brackets 10, and clamp the rail 2, and the legs, firmly in place so they cannot be removed from the top 1 without removing the brackets.

20 The legs 5 are secured to the top 1 by passing the lugs 13, on the rack 2, into the opening *c*, and when the legs are carried around to the position shown in Fig. 1 the lugs are held in place in the dovetailed portion *d* of the slot *c-d* so the legs cannot be swung to the position shown in Figs. 2 and 4, or removed from the top until the rail 2 is straightened and the lugs 13 have passed into the open part *c* of the slot *c-d*, in which position the rail is held in place by the brackets 10 and 12, as hereinbefore stated.

What I claim as new, and desire to secure by Letters Patent of the United States, is:

35 1. In combination with a bench top, centrally divided rails pivotally connected to form a ship lap joint adjacent to the longitudinal centers of the two rails, bevel-connections formed at the meeting ends of 40 the ship laps in the rails for holding them temporarily in extended position, and brackets for holding each rail in operative position.

2. In combination with a bench top having properly formed slots therein, brackets secured to the top to form bearings for revoluble rails, said rails being divided to form a ship lap adjacent its longitudinal center, braces secured to the rail at the pivot point, 45 legs secured at one end to the rails and at the other ends to the braces, dovetailed lugs mounted on one side of the said rails in positions to be made to engage the slots in the bench top, and braces for holding the

legs from movement lengthwise of the 55 bench.

3. In combination with a bench top having segmental slots therein, said slots arranged to form open spaces at one end and a dovetailed bearing at the other end of each 60 slot, rails having dovetailed lugs arranged to be made to enter the slots, brackets secured to the top adjacent to the slots and in position to form bearings for the rails, segmentally formed lugs on the brackets, corresponding brackets on the rails arranged to engage the lugs on the first named brackets, the top having a central slot, the rail divided near its longitudinal center to form a ship lap joint and pivotally connected, 70 braces properly connected with the legs and the bench top, and means for securing the free ends of the braces to the bench top for temporarily securing the legs in extended position.

4. In combination with a bench top having slots in its lower surface, certain of said slots forming dovetailed bearings, a centrally divided and pivotally connected rail, dovetailed lugs on one side of said rail in 80 position to be made to engage the dovetailed slots, braces pivotally connected at the longitudinal center of the rail, legs mounted on the rail with one end of each leg connected with the other ends of said braces, side 85 braces pivotally connected with the legs and arranged to be swung from side to side of the legs, brackets secured to the bench top in position to receive and hold the ends of side braces.

5. In combination with a bench top having properly formed slots in its lower surface, brackets thereon forming bearings, a rail centrally divided and having pivotal connection and locked joints when in alignment, legs mounted on the rail, braces pivotally connected with the pivotal connection of the rail, the opposite ends of the braces rigidly connected with the legs, side braces pivotally mounted on the legs, brackets secured to the bench top in position to be engaged by the ends of the side braces, and means for securing the ends of the legs to the surface of the top so they cannot swing out of position.

Signed at Grand Rapids, Michigan,
March 15, 1917.

PETER G. DAMSTRA.
